DESIGN FOR A TEXTILE FABRIC

Marcel Christen, New York, N. Y.

Application February 5, 1940, Serial No. 90,026

Term of patent 3½ years

To all whom it may concern:

Be it known that I, Marcel Christen, a citizen of the United States of America, residing in New York city, in the Borough of Manhattan, County and State of New York, have invented a new, original, and ornamental Design for a Textile Fabric, of which the following is a specification, reference being had to the accompanying drawing, forming part thereof, wherein,

The figure is a plan view of a piece of textile fabric showing my new design, which is repeated between the selvage edges of the fabric, as shown.

I claim:

The ornamental design for a textile fabric, substantially as shown and described.

MARCEL CHRISTEN.
